PROCESS OF FORMING A LENS BLANK

CROSS REFERENCE TO RELATED APPLICATIONS

This application is a division of my copending application Ser. No. 582,931, filed Sept. 29, 1966, now U.S. Pat. No. 3,449,198, dated Jun. 10, 1969.

The present invention relates to a method for forming lenses and to a lens blank used in said method.

Various means are available in the prior art for holding a glass molded blank during grinding and polishing or, in other words, during the generating of a desired surface configuration on the blank. For example, adhesive may be used to attach a plastic or metal adapter to the molded blank, or the blank may be mechanically gripped into an adapter, or vacuum may be used for holding the blank into or against an adapter. As further alternatives, the blank may be placed loosely into an adapter or a low melting point alloy adapter may be molded directly to the blank. Each of these methods has one or more of the following disadvantages. Accurate alignment of the lens blank cannot be obtained and maintained in progressing from the grinding to the polishing operation. The adapter must be attached to and removed from the lens blank which requires time and labor and in some cases requires expensive apparatus. Handling of the lens blank and adapter is complicated and thus requires labor skill and time.

Consequently, one object of this invention is to provide a method for forming lenses which permits accurate alignment of the lens blank in progressing from and through the grinding to and through the polishing operation.

A further object of this invention is to provide a method for forming lenses which makes unnecessary the attaching of an adapter to the lens for grinding at least one face of the lens.

Still another object of the invention is to provide a method for forming lenses which eliminates the necessity of a separate removal of an adapter from the lens.

A further object of the present invention is to provide a method for forming lenses which simplifies the handling of lenses as compared to the use of mechanical or loose adapters.

A further object of the present invention is to provide an improved method for forming lenses.

One embodiment of the process of this invention might involve the steps of molding a lens blank to have a pair of faces and an integral nubbin adapter on one of said faces, abrading the other of said faces with an abrading means to generate a desired surface configuration, retaining said lens blank against said abrading means with a retainer formed to engage said nubbin adapter, and abrading said one face to remove said nubbin adapter and to generate a desired surface configuration.

The full nature of the invention will be understood from the accompanying drawings and the following description and claims.

FIG. 1 is a perspective view, with certain portions removed for clarity, of apparatus for grinding a lens blank according to the present invention.

FIG. 2 is an enlarged vertical section taken through a portion of the structure of FIG. 1 and showing the lens blank nubbin adapter and associated structure.

FIG. 3 is a top plan view of the lens blank of the present invention.

FIG. 4 is a side elevation of apparatus used in one of the steps of the process of the present invention.

For the purposes of promoting an understanding of the principles of the invention, reference will now be made to the embodiment illustrated in the drawing and specific language will be used to describe the same. It will nevertheless be understood that no limitation of the scope of the invention is thereby intended, such alterations and further modifications in the illustrated device, and such further applications of the principles of the invention as illustrated therein being contemplated as would normally occur to one skilled in the art to which the invention relates.

Referring now more particularly to the drawings, there is illustrated a grinding wheel 10 which has an external peripheral surface 11 formed in the proper toric configuration desired for the concave surface of the lens. The lens 12 is held against the wheel 10 with a pressure supplied by a weight 15 suspended by a cable 16 which extends over a pulley 17 rotatably mounted about a fixed axis 18. The cable 16 acts on an arm 20 through a member 21 secured to the end of the cable 16 and bearing against the lower surface of the end 22 of the arm 20.

A block 25 is rotatably mounted on the arm 20 for swinging about the axis of the cylindrically shaped elongated portion 26 of the arm. The block 25 has secured thereto two pins 27, each of which has a ball shaped distal end 28. In the preferred embodiment of this invention these distal ends are spherical in shape although conceivably other rounded configurations could be used. The ball-shaped distal ends 28 seat in suitable sockets or recesses 30 which open or face away from one another and away from the convex face 31 of the lens blank 12. The recesses 30 are formed within a nubbin adapter 32 molded integrally on the convex face 31 of the lens blank 12. The nubbin adapter 32 extends across substantially the complete surface of the lens blank and has a configuration as shown in FIGS. 2 and 3 which might be termed a "dog bone" shape.

Referring again to FIG. 1, the external shape or configuration of the surface 11 of the wheel 10 may be spherical or may be toric. The wheel 10 is driven so as to rotate about the fixed axis 35 during the grinding operation. The major diameter of the wheel 10 controls the concave curve to be ground on the lens blank in the major or sphere meridian. The curve across the surface 11 of the wheel 10 and lying in the plane of the wheel axis 35 controls the cross-curve to be ground on the lens blank 12.

As the wheel 10 rotates about the axis 35, the lens blank 12 is made to oscillate across the surface 11 of the wheel by an eccentric wheel 40. The wheel 40 is rotatably driven about the fixed axis 39 and is pivotably secured by the link 41 to an oscillating arm 42 which is pivotably mounted for oscillation about a fixed axis 45. As illustrated, the arm 20 is pivoted to the arm 42 at its upper end so that oscillation of the arm 42 also oscillates the arm 20, the block 25 and the lens blank 12.

After the grinding operation has been completed on the concave face of the lens blank, the wheel 10 may be replaced by a polishing wheel of the same or similar spherical or toric configuration and similar apparatus to that illustrated in FIG. 1 used to complete the polishing of the concave face of the lens blank 12. Of course, in conventional manner, slurry is pumped onto the wheel 10 and onto the similarly shaped polishing wheel during both the grinding and the polishing operation.

One of the most important features of the present invention is the fact that the nubbin adapter 32 is molded integrally with the lens blank 12 at the same time that the remainder of the lens blank is molded. Such molding is accomplished by conventional glass molding apparatus such as, for example, a Corning ophthalmic pressing line manufactured by Ophthalmic Division of Corning Glass Company of Herodsburg, Ky. By molding the adapter 32 simultaneously with the molding of the entire lens blank 12, the step of attaching a separate adapter to the lens blank for holding it during the grinding and polishing operation is eliminated.

After the grinding and polishing of the concave surface of the lens blank has been completed, the glass nubbin adapter 32 is removed from the convex surface 31 of the lens blank by the grinding of the convex surface with a conventional ring-tooled diamond generator as shown in FIG. 4. The lens blank 12 may be secured to an adapter in the same manner as is illustrated, for example, in the patent application Ser. No. 384,873 of Tracy H. Calkins and Frank E. Duckwall, now U.S. Pat. No. 3,348,340 dated Oct. 24, 1967.

The grinding of the convex surface 31 may then be accomplished by the apparatus of FIG. 4 which includes a

motor 50 operatively connected to a grinding tool 51 which is applied to the lens' convex surface 31 at a preset angle so as to grind the lens to a desired spherical curvature and thickness. The adapter which has been secured to the concave face of the lens blank 12 is rotated by an electrical motor 52. Of course, grinding is accomplished by the simultaneous rotation of the tool 51 by the motor 50 and rotation of the lens blank 12 by the motor 52. This grinding procedure not only removes the nubbin adapter from the lens blank but also rough grinds the proper spherical shape on the convex side of the lens. Because the nubbin adapter extends substantially completely across the surface 31, uneven wear is not caused on the grinding tool 51.

The lens blank 12 is provided at its outer periphery with at least one flat edge 53 which may be used to reference the lens in any later grinding and polishing operations. Thus the straight edge 53 indicates the direction of the axis of any cylinder shape on the concave surface of the lens blank since the nubbin adapter 32 has now been removed.

The next step in the method of forming the final lens configuration is fine grinding, for example, on the apparatus as illustrated in FIG. 10 of the above mentioned copending patent application. Since this is a conventional procedure and can be accomplished in various ways, it will not be further described herein. Also, the convex surface of the lens blank is polished and can be polished as illustrated and described in connection with FIG. 11 of the above mentioned copending patent application. The manner of removing the adapter of the copending application is fully described in that application and will not be again described herein inasmuch as various procedures can be used for grinding and polishing the convex side of the lens.

It will be evident from the above description that the present invention provides an improved method for forming a lens blank. It will be evident that the present invention makes possible accurate alignment during the complete grinding and polishing operations of the concave surface of the lens blank. This is true because of the fact that the nubbin adapter 32 maintains its exact and precise location on the convex surface 31 of the lens blank 12 during the complete grinding and polishing operations of the concave surface.

It will also be evident that the present invention eliminates the operation of attaching and removing an adapter to the convex side of the lens blank. The attaching is, of course, eliminated because the nubbin adapter 32 is molded simultaneously with the molding of the remainder of the lens blank. The removal of the adapter by a separate step is made unnecessary because the grinding of the convex surface of the lens blank is also used to remove the nubbin adapter. Because a separate adapter need not be connected to the convex surface of the lens blank and removed therefrom, handling of

the lens blank is simplified.

While the invention has been illustrated and described in detail in the drawings and foregoing description, the same is to be considered as illustrative and not restrictive in character, it being understood that only the preferred embodiment has been shown and described and that all changes and modifications that come within the spirit of the invention and the scope of the claims are also desired to be protected.

I claim:

- 10 1. The process of forming a lens which comprises the steps of molding a plurality of lens blanks to have identical configurations each including a pair of faces and an integral nubbin on one of said faces, abrading the other face of said pair of faces of each blank with an abrading means to generate a desired surface configuration, simultaneously retaining each of said lens blanks against said abrading means with a retainer permanently formed in an appropriate configuration to engage the nubbin of said plurality of lens blanks, and abrading said one face of each blank to remove said nubbin 20 and to generate a desired surface configuration.
- 15 2. The process of forming a lens which comprises the steps of:
  - a. molding a plurality of lens blanks to have identical configurations each including a pair of faces and an integral nubbin on one of said faces which extends across substantially the entire one face of each blank and has a pair of recesses formed therein;
  - b. abrading the other face of said pair of faces of each blank with an abrading means to generate a desired surface configuration;
  - c. simultaneously retaining each of said lens blanks against said abrading means with a retainer permanently formed with a pair of rounded elements which seat in said recesses in the nubbin of each blank; and
  - d. abrading said one face of each blank to remove said nubbin and to generate a desired surface configuration.
- 25 3. The process of forming a lens which comprises the steps of:
  - a. molding a lens blank to have a concave face and a convex face and an integral nubbin on said convex face which extends across substantially the entire convex face and has a pair of concave recesses therein spaced from the axis of said lens blank;
  - b. abrading said concave face with a rotatable abrading wheel with a toric outer periphery to generate a desired surface configuration;
  - c. retaining said lens blank against said abrading wheel with a retainer formed to engage said concave recesses; and
  - d. abrading said convex face to remove said nubbin and to generate a desired surface configuration on said convex face.
